UNITED STATES PATENT OFFICE

SIMON BOLIN, OF MENOMINEE, MICHIGAN, ASSIGNOR TO HEYWOOD-WAKEFIELD COMPANY, OF BOSTON, MASSACHUSETTS, A CORPORATION OF MASSACHUSETTS

REED STRUCTURE AND THE LIKE

Application filed January 27, 1926. Serial No. 84,029.

This invention relates to improvements in reed structures and the like and it consists of the matters hereinafter described and more particularly pointed out in the appended 5 claims.

My improved reed structure is especially adapted for use in woven reed fabric of both the "open weave" and "loosely woven" kind wherein the strands are not packed or beaten home into close engagement. Both of such fabrics which may be made of natural reed or reed fibre comprise parallel spaced warp or stake members and parallel spaced weft or filler strand members, usually extending 10 at a right angle to the stake member and laid or woven under one stake and over the other and so on. In the "open weave" fabric the weft or filler strands are spaced such distances apart as to define the large openings 15 by which it receives its name, while in the "loosely woven" fabric, the weft or filler strands though closely adjacent do not engage each other. In both instances, the filler strands are of a diameter less than the stake 20 and more flexible and in the "open weave" fabric the filler strands usually comprise 25 more than one strand member.

When natural reed or reed fibre is employed as the stake members and especially 30 in the open weave and loosely woven fabric, the stakes and strands are comparatively smooth so that the bond or adhesion between them is not sufficient to prevent a relative displacement between said stakes and strands 35 which takes place during the handling of the fabric to which it is normally subjected. Thus the appearance of the fabric is rendered 40 less attractive which of course greatly reduces the sale of the articles in which it is embodied.

One of the objects of the present invention is to provide a reed structure, particularly adapted as the warp or stake member in an "open weave" or "loosely woven" reed fabric, 45 which is so formed that the associated weft or filler strands will have a better engagement therewith whereby the possibilities of relative displacement of said filler strands with respect to said stakes is greatly reduced.

50 A further object of the invention is to so

form the stake member as to not only provide a better engagement with the filler strands, but also to enhance the appearance of the stake itself as well as the finished fabric, and particularly the edges thereof, wherein the 55 stake ends are "waled down" in the fabric in the usual manner to provide a finishing edge therefor.

Still another object of the invention is to provide a reed stake member wherein the 60 outer surface thereof is formed with annular corrugations thereby providing alternating hills and valleys arranged longitudinally of the stake with which the strands of the filler members engage in a manner preventing relative displacement of the stakes and filler 65 strands in the finished article.

The above mentioned objects of the invention, as well as others, together with the many advantages thereof will more fully 70 appear as I proceed with my specification.

In the drawings:

Fig. 1 is a view in elevation of a fragment of "open weave" reed fabric including stake members embodying one form of my invention.

Fig. 2 is a detail horizontal section through the same on an enlarged scale as taken on the line 2-2 of Fig. 1.

Fig. 3 is an enlarged view partly in elevation and partly in section of a reed stake embodying my invention and showing the engagement of the associated filler strands therewith.

Fig. 4 is a view in elevation of a fragment of "loosely woven" fabric including stakes embodying my invention.

Referring now in detail to that embodiment of the invention illustrated in Figs. 1 to 3 inclusive of the accompanying drawing, 1 indicates as a whole a fragment of open weave fabric which includes parallel spaced warps or stakes 2-2 and parallel spaced weft or filler strands 3-3 arranged at a right angle to the stakes as best shown in Fig. 1, thereby 90 providing the large open rectangular spaces 4, whereby the fabric receives its name of "open weave" fabric. The filler strands 3 each comprise two pairs of strand members 5-5 with one pair engaged upon one side of 100

the stakes and with the other pair engaged upon the opposite side of the stakes, the said pairs of members crossing each other between the stakes and taking on an undulatory form, 5 all as best shown in Fig. 1. Each filler strand member is preferably of a diameter less than that of the stake and is made of paper suitably sized and twisted upon itself so as to be readily flexed.

10 As the stakes 2—2 are alike a detailed description of one will suffice for all. As shown herein, each stake is a fibre reed stake as distinguished from a natural reed stake and comprises a fibrous body 6 of paper, suitably sized and twisted upon a metallic core 7 to increase the strength and rigidity of the stake as a whole. The surface of each stake is roughened or otherwise formed to provide strand engaging shoulders thereon. Of course it is preferable to dispose said shoulders thereon in an orderly manner and to this end I find that corrugating the stake circumferentially, provides the most simple and efficient way of so doing. In Fig. 3, the corrugations provide the hills 8 and valleys 9 which are disposed in alternation throughout the entire length of the stake. Said hills and valleys may also be formed helically in the manner of a screw thread or coiled spring 20 but this manner of so forming the same would not be so fast as the first mentioned manner which I prefer to employ. When the strand members of the filler strands are disposed upon the stakes, those portions thereof in actual engagement with the stakes will find a seating or engagement in one or more of the valleys 9 of the stakes and as the pairs of said strand members are twisted or cross each other between the stakes, they are drawn into close contact with the particular valley with which they become associated as best shown in Figs. 2 and 3. With the members engaged in the valleys of the stakes, the hills 8 on each side of those particular valleys act in the manner of opposed shoulders which will prevent the shifting of the filler strands longitudinally upon the stakes.

25 In Fig. 4 I have illustrated the invention as embodied in a "loosely woven" fabric and wherein 2^a indicates the stakes which are made as before described and wherein 3^a indicates the filler strands. In the loosely woven fabric, each filler strand is a single individual member and passes over one side of one stake and under the next stake and so on as distinguished from the duplex filler strands as mentioned in connection with the open weave fabric. However, in the loosely woven fabric, while the strand forming each course 30 is closely disposed with references to the adjacent strands, said strands do not engage the one with the other. It is apparent therefore that there can be no relative slipping between the filler members upon the stake nor no relative displacement between the filler strands

so that the intended relation between the stakes and fillers is always maintained. Again the appearance of the stakes and also the finished fabric is indeed enhanced by removing some of the smoothness of the stakes which are left in a condition better to receive the usual stains or finishes applied thereto. Again in reed fabric of the kind mentioned, a selvage is usually formed on the fabric by "waling down" or bending the projecting ends of the stakes at the edges of the fabric, back upon and into the fabric and with the corrugated stake, this edging is not only greatly improved in appearance, but provides one wherein the waled in ends of the stakes 70 cannot be easily withdrawn.

75 While in describing my invention, I have referred to many details of form and arrangement of the parts thereof, the same is to be taken as by way of illustration only, and not by way of limitation, except as may be pointed out in the appended claims.

80 I claim as my invention:

1. An open weave reed fabric embodying therein parallel spaced uncrimped fibrous stakes and parallel spaced strands arranged at an angle to said stakes and interwoven therewith, said stakes having hills and valleys on opposing surfaces whereby the filler strands seat in the valleys on either side of the stakes and engage the hills in a manner preventing relative movement of the filler strands lengthwise of said stakes.

2. A reed stake structure embodying therein a fibrous stake body and associated interwoven filler strands, said stake body having its surface formed with circumferential corrugations providing alternating hills and valleys, whereby a seating engagement on opposing sides in some of said valleys 105 may be provided for the associated interwoven filler strands.

3. A reed stake structure embodying therein a stake body and associated interwoven filler strands, said stake body having a yieldable surface formed with longitudinally spaced shoulders on opposing sides to provide a seating engagement for the associated filler strands interwoven therewith.

110 In testimony whereof, I have hereunto set my hand this 19th day of January, 1926.

115 SIMON BOLIN.
